UNITED STATES PATENT OFFICE.

HAROLD JAMES GREEN, OF BOLTON, ENGLAND.

GAS-PRODUCER.

1,252,000.

Specification of Letters Patent.

Patented Jan. 1, 1918.

Application filed July 26, 1915. Serial No. 41,929.

To all whom it may concern:

Be it known that I, HAROLD JAMES GREEN, a subject of the King of Great Britain, and a resident of Bolton, Lancashire, England, 5 have invented certain new and useful Improvements in and relating to Gas-Producers, of which the following is a specification.

This invention refers to improvements in 10 and relating to gas producers, and has for its object to enable such producers to deal with fuels containing volatile condensable hydrocarbons in such a manner as to completely convert such hydrocarbons into fixed 15 gases free from tarry matters. The fuels used may be either of a caking or non-caking description, such as the various classes of bituminous coal.

According to this invention, the raw fuel 20 is fed into the interior of the producer by a mechanical stoker, or the like, arranged to deliver the raw fuel in small quantities into the high temperature zone in the lower part of the producer, the rate of feed being adjustable. Means for rotating the grate are provided, to rotate the fuel in this lower part of the producer, so that the stoker feeds the raw fuel into the incandescent bed 25 rotating past it in such manner that the raw fuel is distributed evenly throughout that 30 section of the high temperature zone which passes the feeding point of the stoker.

In a modification, the upper portion of the producer wall is constructed separate 35 from the lower portion of the producer, and means are provided for rotating the upper portion of the producer in the same direction as the grate, such upper portion being preferably supported on rollers, and water seals 40 or the like means may be provided to prevent air leakage between the rotating and non-rotating sections of the producer and the delivery pipe above the producer. Such an arrangement materially assists the rotation 45 of the fuel bed past the feed point of the stoker. With either of the arrangements described, secondary air inlets may be provided about the zone of high temperature, to assist the creation and maintaining of such 50 temperature and the combination of the air with the hydrocarbon distillates to form fixed working gases. Further advantages accrue from the rotation of the fuel inside the producer by means of the rotation of the grate or of the grate and upper part of the 55 producer by means of the rotation of the

producer, inasmuch as such action will tend to consolidate the fuel and prevent arching and the formation of air spaces in the body of the fuel and tendency of clinker to adhere 60 to the producer walls. In construction, the producer will preferably be of the type operating with upward air draft, that is to say, in which air is admitted about the foot of the producer and the products of combustion 65 flow upward to the gas outlet in the upper part of the producer. As far as possible consistent with the invention and the nature of the fuel used, the producer in construction and operation will follow the standard lines 70 of producers which have been successfully developed to use fuel of a more purely carbon nature, such as anthracite.

Gas producers in accordance with this invention are shown in the accompanying 75 drawings, in which Figure 1. is a sectional elevation of a gas producer having a rotary grate and a mechanical stoker arranged to feed the raw fuel into the high temperature zone in the lower part of the producer. 80 Fig. 2. is an analogous view of a gas producer having a rotary grate and mechanical stoker, the latter being inclined, the producer being provided with a system of secondary air admission in the lower part thereof. 85 Fig. 3. is a part sectional elevation of a gas producer illustrating an alternative construction in which the upper portion of the producer wall is built separate from the lower part, means being provided for rotating 90 such upper part and fitting it with water seals. The same letters are used to indicate similar parts throughout the several views.

Referring first to Fig. 1, the producer *a* consists of the usual iron casing of circular 95 section, lined with firebrick or other refractory material, and having a grate and fireplate *b* mounted above the ashtray *b*¹, both being slowly rotated by the pinion *b*³ engaging the gear *b*⁴. The ashtray *b*¹ revolves 100 upon the rollers or ball bearings *f* which in turn rest upon the base plate *b*². A screw *b*⁵ of substantial section supports the weight 105 of the grate and the fuel inside the producer, and by means of this screw the grate may be raised or lowered when the worm wheel *b*⁶ is rotated by a worm, not shown. Raised ribs *e* are provided, preferably cast as part of the fireplate *b*, and engage with and positively rotate the fuel in the lower 110 part of the producer. The raw fuel is contained in a fuel hopper *h* preferably cov-

ered by an air-tight lid h^1 . At the foot of the hopper is a cylinder or the like c penetrating through the producer wall a and directed toward the interior of the producer at about the level of the high temperature zone. A fuel ram r works through this cylinder from the hopper to the interior of the producer, and the cylinder c and fuel ram r are located sufficiently above the fireplate and grate b to avoid interference with the ashes resting thereon when the fuel ram r is in motion. The cylinder c is open to the hopper h so that the raw fuel falls into the cylinder c from the hopper h by gravity when the fuel ram r is at the outer end of its stroke, leaving the cylinder empty for the fuel to enter. The amount of raw fuel allowed each time to fall into the cylinder c is regulated by the movable slide l operated by the pinion r^1 engaging a rack in the top of the slide l . The fuel ram r is operated by the pinion r^1 engaging in a rack on the under side of the ram. The cylinder c may be water-cooled if necessary.

The customary addition of water vapor to the entering air for regulating the temperature of the producer and for enriching the gas is obtained from the funnel o and pipe o^1 which leads to above the fireplate b . A series of pipes may be used, if desired, distributed around the producer. The water will be evaporated by the heat of the fireplate b and the ashes resting thereon, and the fireplate b and the ribs e will be cooled appreciably in consequence, and their liability to be burnt diminished.

If desired, a water pipe may be led from the funnel o to the ashtray b^1 , which latter may be kept more or less full of water and the water vapor from which will also enter the producer with the entering air. Water vapor may also be obtained from a vaporizer situated in any convenient part of the producer or delivery pipe, and be delivered by a pipe or pipes as at n . A delivery pipe d is fitted through which the gas is drawn from the producer. Poking holes p are arranged in the upper cover of the producer to allow of "parallel" poking in the interior of the producer if desired. An inspection tube i is fitted with an air-tight mica or thick glass eyepiece to allow of the height of the fuel in the interior of the producer being readily ascertained. The producer is supported upon standards m . The mechanism for operating the fuel ram r and rotating the grate b and timing the periods at which the fuel ram feeds may be of any suitable design, and is not limited to any particular construction.

When in operation, the air and water vapor will enter the producer at the foot and the resultant gas will be drawn off by the delivery pipe d . The grate and fireplate b will be slowly rotated, carrying with them

the fuel in the lower part of the producer, which action will be assisted by the radiating ribs e cast on the fireplate b . It will also be further assisted by constructing that portion of the producer wall surrounding the feeding zone of the stoker in the shape of a truncated cone, as indicated at a^2 , by reason of which the friction of the fuel along the producer wall will be diminished. The fuel hopper h being filled with raw fuel as required and with the fuel ram r at the outer end of its stroke, the raw fuel will fall by gravity into the cylinder c , the amount depending upon the extent to which the slide l is opened. The fuel ram r operated by the pinion r^1 will then move inward at any desired speed and drive the raw fuel out of the cylinder c into the high temperature zone in the lower part of the producer. To avoid any tendency to jam the ram r by the fuel, I may construct the cylinder c of oval section, and allow a certain amount of clearance above the fuel ram r when passing through the cylinder c . Also, I may form the end r^3 of the fuel ram r which enters into the fuel in the interior of the producer of wedge shape, as shown in the drawing, so that the ram r will tend to lift the fuel upward rather than push it radially toward the center, or laterally in the same plane. When the fuel ram r has reached the end of its stroke, it will be drawn back by the pinion r^1 to its normal position at the outer end of the cylinder c , and another charge of raw fuel will fall into the cylinder c and remain there until the stroke is to be repeated. Concurrently with the above, the fireplate and grate b will be slowly rotated, taking with them the hot fuel in the lower part of the producer, by which means, high temperature fuel will pass the feeding point of the stoker. After any desired rotation of the fuel bed has taken place, the ram r will repeat its stroke and deliver another charge of raw fuel into the high temperature zone at a point distinct from that of the previous stroke. By continuing this cycle of operations, the raw fuel will be distributed regularly and evenly throughout the high temperature feeding zone in the lower part of the producer. The raw fuel cannot, therefore, accumulate in a large compact mass in the producer, so as to exercise a chilling effect upon the incandescent fuel surrounding it. Owing, therefore, to its efficient distribution and small regular rate of feed the temperature of the producer will be maintained and the volatile hydrocarbons in the raw fuel will instantly commence to distil after insertion, and the fuel will be effectively coked. There will be little tendency for the fuel to cake during distillation as the raw fuel will be surrounded by incandescent fuel which is already coked. Any tendency in this direction would

be broken up by the movement of the fuel consequent upon the rotation of the grate and by the agitation of the fuel produced by the inward motion of the ram. The small regular rate of feed will insure that there will be no spontaneous evolution of hydrocarbon gases in excessive quantities such as would take place if a large supply of raw fuel were suddenly introduced into the producer. Owing to the proximity of the raw fuel under distillation to the air supply from the grate, and to the small amount of hydrocarbons liberated at any period, there will be an ample supply of air to produce the necessary temperature to split up these hydrocarbons into their component gases and to combine with them and with any free carbon present to form fixed and permanent gases of high calorific value.

When using inferior fuels, especially of small size, the necessary temperature for the reduction of the gases will not be obtained so easily and I may provide secondary air inlets about the high temperature zone to assist in creating and maintaining such temperature. This secondary air admission may also be used when the producer is to use fuels in which the volatile hydrocarbons are in excess.

Such an application of the invention is illustrated in the producer shown in Fig. 2. Secondary air inlets *s* are provided about the incandescent zone in the lower part of the producer adapted to supply additional air to assist in creating and maintaining a zone of high temperature at the temperature necessary for the effective breaking up of the hydrocarbons and for their proper combination to form fixed working gases. These secondary air inlets may be suitably controlled by valves, or other approved means, if desired. In Fig. 2, an alternative construction of the stoker is shown in which the fuel ram *r* and cylinder *c* are inclined at an angle and directed toward the upper part of the producer. The feeding action of the stoker is otherwise the same as in Fig. 1.

In Fig. 3, is illustrated an alternative construction of producer in which that section of the producer wall *a*¹ into which the stoker cylinder is built is constructed separate from the upper portion *a*. This lower section *a*¹ is supported by and fastened to the standards *m*. The upper portion *a* rests and revolves upon the rollers *f*¹, which are fixed to the standards *m*. A gear wheel *g* engaging a gear *g*¹ attached to and surrounding the producer casing rotates this upper portion *a* of the producer in the same direction as the grate *b* rotates. The friction of the fuel against the inside wall of this upper section will revolve the fuel with it and thus assist the action of the grate in rotating the fuel in the lower part of the producer past

the feeding point of the stoker. A water seal *w* is provided between the stationary lower section *a*¹ and the rotating section *a* to prevent air leakage into the producer, and a second water seal *w*¹ is placed between the non-rotating and rotating sections of the delivery pipe *d* for a similar purpose. In order to prevent excessive evaporation of the water in this delivery pipe seal by the heat of the gas from the producer the iron casings containing and dipping into the sealing water are extended downward for some distance as shown in Fig. 3, in order to provide an air space *w*³ between them and the delivery pipe *d* and lessen the amount of heat transferred by conduction along the iron casing itself.

Make-up water may be allowed to drip into each of these seals, and overflow pipes fitted if desired. The lower stationary section *a*¹ may be either lined with firebrick or other refractory material similar to the producer walls, or it may be constructed hollow to contain water and so act as a water vaporizer, as illustrated in Fig. 3. This would supply water vapor to the fire-grate, for mixing with the entering air passing into the producer, by way of the pipe or pipes as at *n*, and would also have the further advantage of presenting a smooth metallic inner surface which would offer a minimum of friction to the rotating fuel. This construction of vaporizer may also be applied to either of the producers illustrated in Figs. 1. or 2. Further, instead of the raw fuel falling by gravity from the hopper *h* into the cylinder *c*, as shown in Figs. 1. and 2., I may provide a second ram or piston *r*² working at the foot of the hopper *h* at the entrance to a passage *c*¹ leading to the inclined cylinder *c*. The auxiliary ram *r*² will gradually push the raw fuel through this passage into the cylinder *c* and thus positively feed the raw fuel at any desired rate. The stroke of the auxiliary ram *r*² lends itself readily to adjustment, by which means the rate of feed of raw fuel into the producer may be readily varied. In order to prevent excessive air leakage past the fuel ram *r* and auxiliary ram *r*², I may provide a light packing gland *r*³ to one or both of the rams as shown in the drawing, if experience should prove it desirable.

The producers illustrated are all of the open grate type, but it is not necessary that this construction should be followed, as the producer casing may be continued to the ground and the grate space inclosed. Water lutes may also be provided for removing the ashes from this inclosed space. The air passing through all or any of the inlets, and especially the secondary air inlets, may be previously heated if desired. The apparatus illustrated, *b*⁵, *b*⁶, in the various producers, for raising and lowering the grates for the

removal of clinker and ashes inside the producers, need not be adhered to if desired, and any approved design may be substituted. Also, the mechanism for driving the 5 mechanical stoker and rotating the grate, and in Fig. 3, rotating the upper section *a* of the producer, may be of any suitable design. The speed of the driving gear may also be varied by speed cones or any other 10 device.

The fuel hoppers *h* are shown in the drawings as each covered by an airtight lid, but if desired they may be constructed in the manner common to suction gas producers, of 15 the anthracite fuel type, in which an airtight slide or valve is provided underneath the lid or cover at the top of the hopper, which slide is only opened when the raw fuel has been placed upon it and the upper lid 20 closed. This design, of course, is to prevent the admission of air through the fuel hopper to the producer when refilling the fuel hopper.

The temperature of the producer may be 25 modified by the customary admission of water, either in vaporous or liquid form, to all or any of the air inlets, or by any other approved means. If the water vapor is used it may be generated in any convenient manner, such as by heat from the generator itself 30 or from the gaseous product or from an outside source.

To start the producer, the upper portion 35 of the fuel space up to about the working level may be filled with gas coke, or in an alternative method, after the wood chips oily waste or the like has been laid on the grate and the producer filled to about half-way up to the working level. A second layer 40 of wood chips, oily waste, or the like may then be laid over this lower fuel and the fire started at this upper layer, and more fuel added until the producer is filled to about the working level. After the fire has been 45 well blown by the fan, the fire may be started in the lower half and the fan kept going

until the fuel is observed to be in a state of incandescence.

The features of employing secondary air admission to a gas producer, and of rotating 50 certain sections of the producer by gears, and the employment of water seals in connection therewith, have already been proposed, and I make no claims for these features by themselves, but only in the improved combination and construction which 55 constitutes my present invention.

I claim:—

1. In a gas producer, in combination; a producer for containing fuel; having an upper part separate and rotatable and a lower fixed part; means for rotating the upper part; means for feeding raw fuel in small charges into the lower fixed part and through the side thereof; a fixed delivery pipe from the upper rotary part; water seals between the delivery pipe and the rotary upper part; and such rotary upper part and the fixed lower part; and a rotary grate for 60 rotating the fuel past the feeding point.

2. In a gas producer, a producing chamber for containing fuel, a rotary hollow grate in the producing chamber, means for rotating the grate, means for adjusting the grate vertically, a hopper supported adjacent the gas producer and in communication therewith, a reciprocating conveyer operating adjacent the lower end of the hopper for forcing material from the hopper into the producing chamber, means for forcing air 70 under the grate, ribs on the upper surface of the grate for agitating the material in the producing chamber and a gas exhaust pipe in the upper part of the gas producer for 75 exhausting gas therefrom.

In testimony whereof I affix my signature in presence of two witnesses.

HAROLD JAMES GREEN.
